STRAIGHTENING APPARATUS

Ernest E. Brayshaw, Pittsburgh, Pa., assignor to
Carnegie-Illinois Steel Corporation, a corpora-
tion of New Jersey

Application August 30, 1946, Serial No. 693,869

2 Claims. (Cl. 153—54)

1

This invention relates to a straightening apparatus, and more particularly to one which is adapted to the straightening of metallic sections such as bars or plates.

When hot-rolled bars and plates are cooled, twisting and bending often occurs which results in undesirable "sweep" or "camber." "Sweep" is manifested by a longitudinal curve when the section is viewed in side elevation, while "camber" is a longitudinal curve which appears when the section is viewed in plan.

Heretofore a number of methods have been proposed for removing sweep and/or camber in a section of the type described, but so far as I am aware none of these have been entirely satisfactory. Most frequently sweep in a bar or plate is removed by passing the section through a conventional roller-type straightener; and camber is separately removed by a gag press. This two-step method of straightening is unsatisfactory for the reason that two machines are required, which necessitates rehandling, thereby eliminating all possibility of continuous straight line production. In addition, the operation of the gag press so as to completely remove the camber requires considerable time.

It is among the objects of the present invention to simultaneously remove camber and sweep from metallic sections such as bars, plates, etc.

Another object is the attainment of the foregoing by the use of an apparatus which is simple and inexpensive to install, operate, and maintain.

The invention, then, comprises the features hereinafter described and as particularly pointed out in the claims, the following description and the annexed drawings setting forth in detail certain illustrative embodiments of the invention, these being indicative of several of the number of ways in which the principles of the invention may be employed.

In said drawings:

Figure 1 is a side elevation of the apparatus of the present invention;

Figure 2 is a sectional view on the line II—II of Figure 1;

Figure 3 is a view similar to Figure 2, but illustrating a modification;

Figure 4 is an elevational view, partly in section, of one of the rolls of Figure 2; and

Figure 5 is an elevation, partly in section, of a modified type of roll.

Referring more particularly to the drawings, the numeral 2 designates a horizontal lower frame member which supports a plurality of shafts 3 which project therefrom in an overhanging man-

2

ner and occupy a common horizontal plane. It will be understood by those skilled in the art that the shafts 3 may be supported further inwardly by a frame member in addition to the frame member 2, and that the said shafts are suitably power driven for unitary rotation.

The overhanging portion of each of the shafts 3 is provided with an end 4 of reduced diameter, as shown most clearly in Figure 2.

Counting from the left-hand end of Figure 2, the first, second and fourth of the shafts 3 are each provided with a roll barrel 5 which occupies a substantial part of its reduced end 4, and at the outer end of the latter there is carried an enlarged disk 6 which, together with the roll barrel, is held in position by means of a nut 8 and lock washer 9.

Referring still to Figure 2, the third of the shafts 3 is provided with a roll barrel 10 which on its outer end abuts a washer 9 and extends inwardly to seat against an enlarged disk 12 which occupies the extreme inner position of the reduced end 4 of this shaft. As shown in Figures 2 and 4, the roll barrel 10 is provided with a longitudinally extending keyway 13. Onto the inner end of the roll barrel 10 there is telescoped a series of disks 14, 15 and 16, whose outer diameters are substantially the same as that of the outer diameter of the enlarged disk 12. Of this series of disks (i. e. 14, 15 and 16) the outer face of the disk 14 directly abuts against the adjacent face of the enlarged disk 12, while the outer face of the disk 16 abuts against an enlarged disk 17 which likewise telescopes onto the roll barrel 10 and corresponds in shape and size to the enlarged disks 6 on the first, second and fourth rolls, previously described.

The inner faces of the enlarged disks 6 (on the first, second and fourth of the shafts 3) and the outer face of the enlarged disk 17, define the sides of a rolling pass, the remainder of which will shortly be described.

Referring to Figure 4, it will be noted that the enlarged disk 17 is prevented from rotation with the roll barrel 10 by means of a set screw 18, the inner end of which seats in the keyway 13. Thus, the enlarged disk 17 is longitudinally adjustable throughout the length of the roll barrel 10, and by adding or eliminating disks (of the shape and size of the disks 14, 15 and 16) between it and the inner extremity of the reduced end 4 of the shaft 3 a wide latitude of adjustment is permitted, with the result that the width of the pass may be accurately adjusted without removing the roll barrel 10.

In addition, it will be understood that in lieu of the structure shown in Figure 2, the inner disk 12 may be formed integrally with the inner end of the roll barrel 10, as shown in Figure 4.

Referring to Figure 1, immediately above the frame member 2 there is disposed a horizontal upper frame member 19 which is similar in construction. This frame member 19 supports a plurality of overhanging shafts 20 which occupy a common horizontal plane. On each of these shafts 20 there is carried a roll barrel. The second, third and fourth of the shafts 20 carry cylindrical roll barrels 21, while the first of the shafts 20 carries a roll of modified construction. More specifically, this first or initial roll of modified construction comprises a cylindrical roll barrel 22 of the same diameter as the roll barrels 21, but embodying on its outer end a reduced or relieved portion 23 which accommodates the enlarged disk 6 on the first of the lower shafts 3.

The upper shafts 20 may be supported further inwardly by a frame member in addition to the frame element 19; and means (not shown) are provided for making each of the said shafts 20 vertically adjustable. While the first or initial of the shafts 20 is disposed directly above the corresponding lower shaft 3, the second, third and fourth of the shafts 20 are offset slightly rearwardly of the corresponding lower roll, as shown in Figure 1.

Between the lower and upper frame members 2 and 19, respectively, there is disposed a pair of widely spaced and suitably supported bifurcated arms 25, each of which carries a vertically disposed idle roll 27 which is adapted to contact the inner edge of the section to be straightened, the latter being shown at 29. Preferably a vertical idle roll 27 and its bifurcated supporting arm 25 is disposed at both the inlet and outlet of the straightening apparatus of the invention, and if desired the same may be employed in one or more opposing pairs, as shown in Figure 3, whereby the outer edge of the section 29 is also contacted.

In Figure 3 of the drawings there is disclosed a pair of parallel horizontal lower frame members 32 for supporting the lower shafts, the latter in this case being designated at 33. According to this construction the lower rotary shafts are fully supported in lieu of the outboard relationship shown in Figures 1 and 2. While the detailed construction of the built-up roll (i. e. roll barrel 10 and associated instrumentalities) is essentially the same as that shown in Figures 2 and 4, two of the said rolls are employed, i. e. one on the second and one on the fourth of the lower shafts 33.

Referring to Figure 5, there is shown a modified built-up roll which takes the form of a roll barrel 40 provided on its inner end with an integrally-formed enlarged disk 42, disks 44, 45 and 46 being provided between the outer end of the roll barrel 40 and the end of the reduced section 4 of the shaft 3.

In operation, the roll 22 serves as an upper pinch roll to hold the section 29 against the roll barrel 5 of the first of the lower rolls. Then, the roll barrel 5 of the second lower roll forces the section upwardly and the second of the upper rolls forces it downwardly, thereby imparting to the section a positive sweep. The following rolls

are adjusted to remove this sweep as the section continues through the straightening apparatus. For removal of camber in the section 29 it is directed by the entry idle roll 27 against the enlarged disks or collars 6 of the first two bottom rolls, thereby imparting to the section a positive camber. The third and fourth bottom rolls and the outlet idle roll 27 are so adjusted as to remove the camber.

10 While I have shown and described certain specific embodiments of the present invention, it will be readily understood by those skilled in the art that I do not wish to be limited exactly thereto, since various modifications may be made without departing from the scope of the invention as defined in the appended claims.

I claim:

1. A straightening apparatus for metallic sections comprising a series of power-driven rolls the axes of which occupy a common plane, a collar on the first of said rolls, a collar on another of said rolls, said last-named collar occupying a different longitudinal position on its carrying roll than said first-named collar, whereby there is defined by and between said collars the sides of a rolling pass, and a series of idle rolls the axes of which occupy a plane which is parallel and adjacent the plane of said series of power-driven rolls, the first of said series of idle rolls having a reduced diameter portion contacting the periphery of the collar of the first of said power-driven rolls and a main portion spaced from the main portion of the first of said power-driven rolls to form a pinch pass for feeding the section into the straightening apparatus.

2. A straightening apparatus for metallic sections comprising a series of power-driven rolls the axes of which occupy a common plane, a collar on the first of said rolls, a collar on another of said rolls, said last-named collar occupying a different longitudinal position on its carrying roll than said first-named collar, whereby there is defined by and between said collars the sides of a rolling pass, and a series of idle rolls the axes of which occupy a plane which is parallel and adjacent the plane of said series of power-driven rolls, the first of said series of idle rolls having a reduced diameter portion contacting the periphery of the collar of the first of said power-driven rolls and a main portion spaced from the main portion of the first of said power-driven rolls to form a pinch pass for feeding the section into the straightening apparatus, at least one of said collars being longitudinally adjustable with respect to its carrying roll whereby the width of the rolling pass may be adjusted.

ERNEST E. BRAYSHAW.
